SHOE COUNTER

Arthur C. Engel, Haverhill, Mass.

Application March 16, 1935, Serial No. 11,464

8 Claims. (Cl. 36—68)

The present invention relates to shoe counters and blanks therefor, and more particularly to counters of the molded type. Counters of the above-described character have a back and two oppositely disposed sides; and they are so rolled so as to impart to their sides an exteriorly convex shape, in order that the upper edges of the said sides may extend toward each other, and to cause a better fit against the correspondingly shaped heel portion of the foot. The interior structure of the material of the counter becomes violently deformed during the shaping process, so that the counter has a tendency to return toward its original, unshaped condition. The said upper edges of the said sides of the counters, therefore, spring back, away from each other, thus impairing the shape that it was intended to impart to the counter by the rolling process.

An object of the invention is to minimize this spring-back tendency.

With this end in view, a feature of the invention resides in making the said sides of the counter of non-uniform rigidity or thickness in regions spaced between their upper and lower edges, preferably by digging a plurality of grooves disposed in substantially horizontal or inclined planes. There will then be less tendency for the material of the counter to work back to its original, internal construction, so that the counter will tend to hold its shape, and the shoe will fit better on the foot.

Other and further objects will be explained hereinafter, and will be particularly pointed out in the appended claims.

The invention will now be explained in connection with the accompanying drawings, in which Fig. 1 is a view of a counter blank from which the counter embodying the present invention may be manufactured; Fig. 2 is a perspective of a preferred embodiment of the present invention, partly in section upon the line 2—2 of Fig. 1, looking in the direction of the arrows, upon a larger scale than in Fig. 1; Fig. 3 is a vertical section, partly in elevation, upon the same scale as in Fig. 2, illustrating a step in the manufacture of the counter of the present invention, the section being taken upon the line 3—3 of Fig. 9, looking in the directions of the arrows; Fig. 4 is a perspective, on the same, larger scale, of a counter made from the blank shown in Figs. 1 and 2 in accordance with the present invention; Fig. 5 is a plan of a shoe, showing in dotted and dot-and-dash lines the relative positions occupied by a counter embodying the present invention and a counter of the prior art, Fig. 6 is

an elevation of the same, the counter of the present invention being shown in dotted lines; Figs. 7 and 8 are perspectives of modified counters embodying the present invention; and Fig. 9 is a section taken upon the line 9—9 of Fig. 3, looking in the direction of the arrows, but upon a smaller scale than in Fig. 3.

The counter of the present invention is of the type that is made of sheet material, such as leather or fibre. It may be made from a sheet blank, such as is shown in Fig. 1, having sides 4 and 6 extending in opposite directions from its intermediate part, which intermediate part constitutes the back of the completed and shaped counter. The blank is passed between convex and concave rollers 1 and 2 and then between the convex roller 1 and a concave die or mold 1 that is pressed towards the convex roller 1 by a stiff spring 9. A transversely curved shape, as illustrated in section in Figs. 2 and 3, is thus imparted to the blank. After the counter has been molded into U-form, as shown more particularly in Figs. 4, 7 and 8, its sides 4 and 6, because of the convexity imparted to the counter blank by the rollers 1 and 2 and the cup 1, will be exteriorly convexely curved, so that the upper, skived edges 3 and 5 of the sides 4 and 6 will extend toward each other, as illustrated by dotted lines in Fig. 5.

As the leather, fibre or other material of which the counter is made tends to work back, or become restored, to its original, unmolded and unrolled or otherwise undeformed shape, particularly because the counter is worked in temper or moisture, the upper edges 3 and 5 of the sides 4 and 6 of the counter tend to spring back from the dotted lines 3 and 5 to the dot-and-dash lines 23 and 21 of Fig. 5. This destroys the shape of the shoe and the fit upon the foot; and is particularly objectionable when the fibre board is constituted of a vegetable pulp product, impregnated with sizing treated with wax or a similar substance during the above-described rolling process between the rolls 1 and 3 and the cup-shaped die 1, as this rolling process tends to solidify the impregnating sizing and the wax into the counter and fix its shape and stiffen it against change of shape, so that any tendency later to deform it during the U-shaping process is greatly resisted by the resulting internal constitution of the counter.

According to a preferred embodiment of the present invention, this is prevented by making the counter of less thickness or rigidity in regions 25 spaced between the upper edges 3 and 5 of the sides 4 and 6 and the inturned bottom flange 55

8 than in the regions 27 between the regions 25. Because of the less thickness or rigidity of the material of the counter in the regions 25 at portions of the counter substantially removed from the back of the counter, there is less tendency for the stock to work back to its original molecular constitution, with the result that, after the upper edges 3 and 5 have been thrown forward toward the lines of the foot by the above-described rolling and molding operations, the counter will hold the above-described rolled or curved shape, illustrated by the dotted lines 3 and 5 in Fig. 5; and will not work back toward the dot-and-dash lines 23 and 21.

15 The counter of the present invention, on the other hand, retains its shape and flexibility; in fact, fibre-board counters of the above-described type made according to the present invention have all the flexibility of leather counters. The new counter is even more flexible and better fitting than counters that are not built according to the present invention, so that the shoe will conform better to the wearer's foot and add to his comfort, besides preventing the formation of lesions on the foot, as so often occurs with poorly fitting, fibre-board counters.

It is preferred to produce the desired result of facilitating the sides 4 and 6 holding their curved shape by grooving the counter along the regions 25. Preferably, the grooves may be in substantially horizontal planes, and separated from each other in each plane by walls 29 of substantially the same thickness as the thickness of the body of the counter, constituted of the regions 27. To this end, the roll 1, for example, may be provided with corrugations or teeth 31, which will produce the grooves 25 by working into the blank during the rolling process illustrated in Fig. 3. The teeth 31 are shown more or less V-shaped in section. Because of the presence of the teeth 31, it is preferred to employ a stripper 10 to facilitate removing the convexed blank from the roll 1 as it leaves the machine. Preferably, as illustrated, the grooves extend, not through the entire wall of the counter, but only part way thereinto, from the inner surface of the counter outward, leaving the outer surface of the counter intact. The walls 29 are preferably made relatively very small, as illustrated, so as to provide a greater aggregate area over which the grooves 25 are disposed. The grooves 25 need not necessarily be all of the same depth. On the contrary, the grooves near the edges 3 and 5, for example, will usually be of less depth than other grooves because the edges 3 and 5 are usually skived, as illustrated more particularly in Fig. 2. Such skived edges are usually less stiff than the body of the counter and do not, therefore, usually require so deep grooves 25.

60 The cost of manufacture of the counters of the present invention is thus no greater than of counters made today; for the new counter, with all its advantages, is prepared by the same rolling operation as present-day counters.

65 The present invention may be embodied in any type of counter, long or short, and with equal or unequal sides 4 and 6. In Figs. 4 and 8, for example, the sides 4 and 6 of the counter are of equal length; in Fig. 4, the counter is shown as of the long type and, in Fig. 8, as of the short type. The counter illustrated in Fig. 7 has one side 4 longer than the other side 6.

70 It will also be understood that it is not strictly necessary that the grooves 25 be disposed in substantially horizontal planes. The planes of the

grooves may be inclined somewhat, or even to a considerable degree. The same effects will be produced as described above.

Further modifications will occur to persons skilled in the art, and all such are considered to fall within the spirit and scope of the invention, as defined in the appended claims.

What is claimed is:

1. A counter of deformed sheet material of U-shape for use in a shoe and having a back and two oppositely disposed sides, the sheet material being of a nature that has a tendency to become restored toward its undeformed condition, the counter having both its said sides exteriorly convexed curved so that their upper edges extend toward each other, and portions of the said sides substantially removed from the said back of the counter being of less rigidity in regions spaced between the upper and lower edges of the said sides than in the regions between the spaced regions to facilitate their holding the said sides deformed, curved shape. 15

2. A counter of deformed sheet material of U-shape for use in a shoe and having a back and two oppositely disposed sides, the sheet material being of a nature that has a tendency to become restored toward its undeformed condition, the counter having both its said sides exteriorly convexed curved so that their upper edges extend toward each other, and portions of the said sides substantially removed from the said back of the counter being of less thickness in regions spaced between the upper and lower edges of the said sides than in the regions between the spaced regions to facilitate their holding the said sides deformed, curved shape. 25

3. A counter of deformed sheet material of U-shape for use in a shoe and having a back and two oppositely disposed sides, the sheet material being of a nature that has a tendency to become restored toward its undeformed condition, the counter having both its said sides exteriorly convexed curved so that their upper edges extend toward each other, and portions of the said sides substantially removed from the said back of the counter having a plurality of grooves to facilitate the said sides holding their deformed, curved shape. 40

4. A counter of sheet material molded into U-form for use in a shoe and having a back and two oppositely disposed sides and an inturned bottom flange, the said sides of the counter being exteriorly convexed curved so that their upper edges extend toward each other, and portions of the said sides substantially removed from the said back of the counter having a plurality of grooves in regions spaced between the upper edges and the flange of the said sides to facilitate the said sides holding their curved shape, the grooves being separated from each other by walls of substantially the same thickness as the thickness of the body of the counter. 45 50

5. A sheet blank for a counter adapted to be shaped into U-form for use in a shoe, the blank being of material that has a tendency to become restored to its undeformed condition after becoming deformed, the blank having two sides extending in opposite directions from an intermediate part, portions of the blank substantially removed from the said intermediate part being of less rigidity in regions spaced between the upper and lower edges of the said sides than in other regions between the spaced regions. 55 60

6. A sheet blank for a counter adapted to be shaped into U-form for use in a shoe, the blank 70 75

- being of material that has a tendency to become restored to its undeformed condition after becoming deformed, the blank having two sides extending in opposite directions from an intermediate part, portions of the blank substantially removed from the said intermediate part being of less thickness in regions spaced between the upper and lower edges of the said sides than in other regions between the spaced regions. 5
- 10 7. A sheet blank for a counter adapted to be shaped into U-form for use in a shoe, the blank being of material that has a tendency to become restored to its undeformed condition after becoming deformed, the blank having two sides 10 extending in opposite directions from an inter-
- mediate part, portions of the blank substantially removed from the said intermediate part having a plurality of grooves. 5
- 15 8. A sheet blank for a counter adapted to be shaped into U-form for use in a shoe, the blank being of material that has a tendency to become restored to its undeformed condition after becoming deformed, the blank having two sides extending in opposite directions from an intermediate part, portions of the blank substantially removed from the said intermediate part having a plurality of grooves separated from each other by walls of substantially the same thickness as the thickness of the body of the blank. 15

ARTHUR C. ENGEL. 15

CERTIFICATE OF CORRECTION.

Patent No. 2,002,093.

May 21, 1935.

ARTHUR C. ENGEL.

It is hereby certified that error appears in the printed specification of the above numbered patent requiring correction as follows: Page 2, second column, lines 21 and 35, claims 1 and 2 respectively, strike out the words "their holding"; and lines 22 and 36, of said claims, before "deformed" insert the words holding their; and that the said Letters Patent should be read with these corrections therein that the same may conform to the record of the case in the Patent Office.

Signed and sealed this 25th day of June, A. D. 1935.

Bryan M. Battey

Acting Commissioner of Patents.
